(Cl. D34—5)

To all whom it may concern:

Be it known that I, Loyal Frederick Roh, a citizen of the United States of America, residing at Grand Rapids, in the county of Kent and State of Michigan, have invented a new, original, and ornamental Design for a Cribbage Board, of which the following is a specification, reference being had to the accompanying drawing, forming a part thereof.

In the drawing:

I claim:

The ornamental design for a cribbage board, as shown.

LOYAL FREDERICK ROH.
